UNITED STATES PATENT OFFICE.

PETER KIMACK, OF ST. LOUIS, MISSOURI.

RAILWAY-RAIL.

1,242,203.

Specification of Letters Patent.

Patented Oct. 9, 1917.

Application filed May 7, 1917. Serial No. 166,954.

To all whom it may concern:

Be it known that I, PETER KIMACK, a citizen of the United States, and resident of St. Louis, in the State of Missouri, have 5 invented certain new and useful Improvements in Railway-Rails, of which the following is a specification, containing a full, clear, and exact description, references being had to the accompanying drawings, 10 forming a part hereof.

My invention relates to improvements in "railway rails" and is especially directed to rails employed in connection with "guards" as for use at frogs, switches, curves and 15 fills.

My object is primarily to construct a running rail by casting integrally therewith a guard rail; and a further object is to construct a running rail having a guard rail 20 and at least at one end an element constituting a joint for connection with an alining rail, by casting with manganese steel and as an integral unit.

My improvements consist in a novel construction of a running rail having an integral guard rail and a joint element, as will be fully, clearly, and concisely set forth in my specifications, pointed out in my 25 claims and illustrated by the accompanying 30 drawing, in which:

Figure 1 is a view, in perspective, of a rail embodying my improvements, showing the arrangement of the "guard" and the joint for connection with a second rail.

Fig. 2 is a transverse, sectional elevation of the rail, taken at its approximate longitudinal center.

Referring to the drawing by numerals, 7 designates the one end of the rail, as 35 shown, which is adapted for use with a frog, and which rail end 7 has base flanges 8, web 9 and ball 10, similar to an ordinary rail, so that it may be joined to an ordinary rail in a common manner, as by fish plates, 40 which I have not deemed it necessary to show.

Next the end 7, extending lengthwise of the rail, the one base flange 8 is extended laterally to form a flange 11, and upstanding therefrom is a web 12 arranged to support a ball 13, constituting a guard paralleling the ball 10.

By preference, the balls 10 and 13 are connected by a bridge 14, occupying a plane 50 beneath the plane of wheel flanges of rolling stock, said bridge providing for a brace

to the guard as well as a "foot guard" between the running and guard rails.

By preference, the ball 13 at each end flares outwardly or laterally away from the 60 ball of the running rail, in order to guide wheel flanges which may have been shifted an abnormal distance from the ball of the running rail.

The rail end 15 beyond the ball 13 has 65 its ball increased in sectional dimensions, on its outside lateral face, as shown at 16 and then reduced to form a lateral extension or joint 17, of such design as to receive against its inside face an ordinary running 70 rail 18, whose ball is held in the plane of the ball 10 and in alinement therewith.

Formed through the rail end 15 and the extension or joint 17, are the bolt holes 19, whereby to secure the joint as by fish plates 75 and bolts in a common manner. This structure as just described, except the running rails mentioned of ordinary construction, is formed as an integral unit cast from manganese steel, and its advantage lies in its 80 economical construction as compared with both running and guards as separate structure, its economical installation, and its rigidity.

In practice I make my improved 85 combined running and guard rail approximately from 12 to 15 feet long for the running rail, and for such lengths of running rail, the guard rail will be approximately about 9 or 12 feet long, the running rail projecting 90 on each end of the guard rail about 18 inches.

Furthermore, in practice I make my combined guard and running rail hollow, as 95 illustrated in Fig. 2, which reduces the weight and does not objectionably affect the strength.

In the illustration I have shown a straight running rail in connection with the combined guard rail, but in instances where I 100 desire to use my invention in connection with frogs, the "lead" rail is slightly curved to correspond to the switch rail curvature, in which instances it should be numbered corresponding to the "lead" of the switch. 105

By the use of my invention the necessity for using rail braces, tie plates, guard rail fillers, bolts, wedges, clamps, and foot blocks is eliminated.

Having thus described my invention, what 110 I claim is:

1. A rail consisting of a single hollow

casting comprising a base, a pair of laterally spaced webs, a pair of laterally spaced balls and a bridge connecting the webs beneath said balls, said bridge extending throughout 5 the guard and acting as a brace for the guard and as a foot guard between the running and guard rails.

2. A rail consisting of a single casting comprising a base, a pair of laterally spaced webs, a pair of laterally spaced balls, a bridge connecting the webs beneath said balls, and said rail being provided at one end with a recessed portion adapted to receive the end of a running rail.

15 3. A rail cast from manganese steel, having a hollow central body portion and comprising a running rail ball and a guard rail ball and inner and outer base flanges ex-

tending throughout the length of the rail, a pair of laterally spaced webs, a bridge connecting the webs and inclosing the space between the webs throughout the length of the guard ball and serving the purpose of a brace for the guard ball and as a foot guard between the balls, one end of the running 25 rail ball being enlarged and a recessed portion formed in said enlarged end adapted to receive the end of a running rail.

In testimony whereof, I have signed my name to this specification, in presence of 30 two subscribing witnesses.

PETER KIMACK.
